J. W. COAST, JR.
ART OF CRACKING HYDROCARBONS.
APPLICATION FILED MAY 22, 1917.

1,252,999.

Patented Jan. 8, 1918.

UNITED STATES PATENT OFFICE.

JOHN W. COAST, JR., OF TULSA, OKLAHOMA, ASSIGNOR TO THE PROCESS COMPANY, OF TULSA, OKLAHOMA, A CORPORATION OF MARYLAND.

ART OF CRACKING HYDROCARBONS.

1,252,999.

Specification of Letters Patent.

Patented Jan. 8, 1918.

Application filed May 22, 1917. Serial No. 170,148.

To all whom it may concern:

Be it known that I, JOHN W. COAST, Jr., a citizen of the United States of America, a resident of Tulsa, in the county of Tulsa, 5 State of Oklahoma, have invented certain new and useful Improvements in the Art of Cracking Hydrocarbons, of which the following is a full, clear, and exact description, reference being had to the accompanying 10 drawings, forming a part of this specification.

My invention relates to improvements in the art of cracking hydrocarbons, and more particularly to a method of protecting over-heated portions of cracking stills.

When high boiling point petroleum hydrocarbons are cracked in the ordinary cylindrical still, heavy coke forming fractions settle on the still bottom. The resultant 20 coke or carbon is a good heat insulator; it prevents the free transmission of heat from the still bottom to the liquid, and it usually accumulates in a pile at some point directly above the fire. When a sufficient quantity 25 of this coke has accumulated, a portion of the bottom of the still soon becomes red hot, and some immediate steps must then be taken to avoid a rupture at the overheated portion of the still. In actual practice, the 30 still is usually permitted to cool and the coke or carbon is then removed. Obviously, this procedure results in a loss of fuel due to the cooling and reheating of the still, the operating expenses are otherwise increased, and 35 the average yield per hour is decreased.

The object of my invention is to eliminate the danger by protecting the overheated portions of the still, thereby increasing the life of the still and permitting it to be operated 40 continuously for a considerable period of time without removing the coke or carbon.

Figure I is a diagrammatical view of a cracking apparatus, showing a shield adapted for use in carrying out my method.

45 Fig. II is a horizontal section, showing the heating chamber and the shield mounted therein.

Fig. III is an enlarged horizontal section, showing the interior of the shield.

50 Fig. IV is a section on the line IV—IV, Fig. III.

To illustrate the invention, I have shown a large cylindrical cracking still 1 arranged above a heating chamber, the latter being 55 provided with a grate 2 on which a bed of

fire is maintained. The vapor passing from the still flows through an inclined vapor pipe 3, then through an air cooled reflux condenser 4 to a vapor pipe 5 leading to a main condenser 6, from which the product is 60 recovered. The condenser 6 is preferably a coil arranged in a water tank 7.

The apparatus I have shown is particularly adapted for use in cracking high boiling point products of distillation, such, for 65 example, as distillates or residues resulting from the distillation of crude petroleum. The substances to be treated are introduced into the still in any suitable manner, and the desired pressure may be obtained by regulating a valve 8, preferably located in the 70 vapor pipe 5. The pressure in the still and reflux condenser 4 is preferably greater than 50 pounds per square inch, and the temperature of the contents of the still preferably 75 ranges from about 600° F. to 800° F. The low boiling point fractions passing from the liquid flow through the vapor pipe 3 and reflux condenser 4 to the pipe 5, leading to the main condenser 6. The relatively high 80 boiling point fractions are condensed in the inclined vapor pipe 3, or in the condenser 4, such fractions being returned to the still 85 through the inclined vapor pipe. This reflux condensate includes a large percentage of heavy, coke forming fractions, commingled with lighter fractions which may be redistilled to form part of the low boiling point product.

A shield A, located in a pocket in the 90 front wall of the heating chamber, is slidably mounted on a horizontal guide consisting of a pair of pipes 9 and 10 connected by a shorter pipe 11 at the front of the still. The pipes 9 and 10, located between the bottom 95 of the still and the fire, are arranged longitudinally of the still. An overflow pipe 9' leads from the condenser to the pipe 9, the water passing from the condenser being circulated through the pipes 9 and 10. 100 The shield A is a hollow fire-proof structure, made of metal and provided with baffles 12 forming passageways for a cooling fluid, preferably water, which flows from a pipe 13 through the shield, and then through a discharge pipe 14. The pipes 13 and 14 extend through the front wall of the heating chamber and serve as handles for manipulating the shield from the exterior 105 of the apparatus. Sleeves 15, forming part 110

of the shield, are loosely fitted to the pipes 9 and 10.

When the still is in service, coke forming fractions will settle on the bottom of the 5 still, and at some point a relatively large body of the coke or carbon will accumulate, as indicated by the dotted lines X in Fig. I. A portion of the still bottom will then be overheated and become red at a point below 10 the coke or carbon. At this time, the operator interposes the shield between the red portion of the still and the heating medium, thereby intercepting the heat so as to protect the coke-covered portion of the still 15 from the heating medium. By protecting the still in this manner, the danger usually due to overheating can be quickly overcome, without cooling the entire still and without removing the coke or carbon from the still. 20 The temperature of the contents of the still is not materially changed, and the continued cracking operation is not materially affected by the relatively small fireproof shield under the large still. 25 The apparatus herein shown is claimed in an application for patent filed by me May 22, 1917, Serial Number 170,147.

I claim:

1. In the art of cracking hydrocarbons, 30 the method of maintaining cracking stills in operation which comprises interposing a

shield between an overheated portion of a still and the heating medium.

2. In the art of treating hydrocarbons, 35 the method which comprises heating a still to transmit heat to the contents thereof, and thereafter interposing a shield between an overheated portion of the still and the heating medium.

3. In the art of cracking hydrocarbons, 40 the method which comprises heating the bottom of a large cylindrical cracking still, and interposing a relatively small shield between the heating medium and an overheated portion of the bottom of the still. 45

4. In the art of cracking hydrocarbons, the method which comprises heating the bottom of a cracking still, permitting coke to accumulate on said bottom, permitting a portion of said bottom to be overheated and become red at a point below said coke, and then interposing a shield between the red portion of the still and the heating medium. 50

5. In the art of cracking hydrocarbons, the method of maintaining cracking stills in 55 operation which comprises interposing a shield between an overheated portion of a still and the heating medium, and circulating a cooling fluid through said shield.

In testimony that I claim the foregoing I 60 hereunto affix my signature.

JOHN W. COAST, JR.
